Aug. 17, 1872.

UNITED STATES PATENT OFFICE.

GUSTAVUS A. BROWN, OF FARMINGTON, MICHIGAN.

DESIGN FOR A TOY STEAM-ENGINE.

Specification forming part of Design No. 6,149, dated September 24, 1872.

To all whom it may concern:

Be it known that I, GUSTAVUS A. BROWN, of Farmington, in the county of Oakland and State of Michigan, have invented a Design for a Glass Engine and Boiler, of which the following is a specification:

The nature of my design is fully represented in the accompanying photographic illustration, to which reference is made.

The object of this design is to enable the teacher or lecturer to illustrate the theory of the steam-engine, both in the condensing and non-condensing form.

A represents a rectangular box, which forms a bed-piece for a metallic skeleton gallows-frame, B, for the beam C of the engine, of which D is the cylinder; E, the side pipe or steam-chest, cylindrical in cross-section; K, the exhaust-drum, connected at top and bottom with the steam-chest, and at the bottom

with the condenser F, with a valve, a, between them. A valve, b, at the top of the exhaust-drum, when opened, allows the exhaust steam to escape into the atmosphere. G is the air-pump, and H is the cold-water-injection pump, provided with the air-chamber H'.

The cylinder, steam-chest, exhaust-drum, condenser, and pumps are of glass with metallic heads, as is also the boiler I, for the purpose of illustrating the theory of steam in its generation and utilization.

What I claim as my invention, and desire to secure by Letters Patent, is—

The design for a combined glass and metallic engine, as shown and set forth.

GUSTAVUS A. BROWN.
